UNITED STATES PATENT OFFICE.

RAYMOND L. CHEATHAM, OF RICHMOND, VIRGINIA.

AUTOMOBILE-BRUSH.

1,392,623.

Specification of Letters Patent.

Patented Oct. 4, 1921.

Application filed October 30, 1920. Serial No. 420,653.

To all whom it may concern:

Be it known that I, RAYMOND L. CHEATHAM, a citizen of the United States, residing at Richmond in the county of Chesterfield and State of Virginia, have invented certain new and useful Improvements in Automobile-Brushes; and I do hereby declare the following to be a full, clear, and exact description of the invention, such as will enable others skilled in the art to which it appertains to make and use the same.

This invention relates to new and useful improvements in brushes especially adapted for washing mud, grit and dust from automobiles or other articles having highly polished paint thereon, and has for its primary object the provision of a device of the above stated character which will loosen foreign matter from a painted surface and remove the same with a flow of clean water so as to obviate scratching or otherwise injuring the painted surface.

A further object of this invention is the provision of a mounting for the cleaning elements, which will form an efficient means for the handling of the device and also permits of said device to be readily and quickly applied to a hose.

A still further object of this invention is the provision of a brush of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:—

Figure 1 is a side elevation, illustrating a brush constructed in accordance with my invention,

Fig. 2 is a top plan view illustrating the same applied to a hose.

Fig. 3 is a vertical sectional view illustrating the mounting of the cleaning elements within the holder,

Fig. 4 is a horizontal sectional view illustrating the same,

Fig. 5 is a perspective view illustrating a cover or protecting element.

Referring in detail to the drawings, the

numeral 1 indicates a casing constructed of aluminum or any other material suitable for the purpose and is of preferably circular formation having its lower end fully open to receive a cleaning element 2. The cleaning element 2 is non-rotatable and consists of a circular frame or head 3 secured to the sides of the casing 1 by suitable fastening elements and located upon the interior of the casing and adjacent the lower edge thereof. The head 3 has secured thereto tufts of bristles 4 constructed from comparatively soft hair or material and which project outwardly of the casing for the purpose of engaging a surface.

A rotatable cleaning element 5 is located within the casing and also within the head 3 of the stationary cleaning element 2 and consists of a head 6 of circular formation and has secured to one face a plurality of tufts of bristles 7 which are of a very soft nature. The head 6 is provided with a centrally arranged opening 8 and each face of the head surrounding said opening 8 is provided with bearing plates 9. The bearing plates 9 are secured to the head 6 by fasteners 10. A spindle 11 has formed upon one end a head 12 provided with arms 13 that are secured to the top wall of the casing 1 by fasteners 14 and said spindle extends downwardly through the opening 8 of the head 6. A nut and washer is positioned on the free end of the spindle for the purpose of retaining the head 6 thereon and to permit the cleaning elements 5 to have free rotation within the casing and within the stationary cleaning element 2.

A band 15 is secured to the periphery of the head 6 and has secured thereto a plurality of radially extending fins or plates 16, the free ends of which terminate in close proximity to the side of the casing 1. A nozzle 17 is formed on the casing 1 and extends from the casing in an inclined plane and has communication with the interior of said casing so that water injected into said nozzle from a hose 18 will strike against the fins or plates 16 to rotate the cleaning element 5. The nozzle 17 is substantially conical shape for the purpose of restricting the flow of water into the casing to a given area and its outer end receives an ordinary nozzle on the end of the hose 18.

A handle 19 is secured to the casing 1 adjacent the nozzle 17 and converges toward said nozzle and has its outer end cut away

to form a flattened portion 20 to which an adjustable hose clamp 21 is secured. The hose clamp 21 is adapted to attach the hose to the handle for the purpose of preventing 5 said hose from coming in contact with the surface on which the brush is operating.

A protecting element 22 constructed from rubber or any other material suitable for the purpose is of a corresponding shape to the 10 casing 1 and is placed over the casing and is provided with cut out portions 23 to receive the nozzle and the handle. The protecting element 22 is adapted to prevent the casing from coming in contact with the article on 15 which the brush is operating thereby obviating any danger of the casing scratching or marring the surface of said article.

The water passing into the casing from the hose strikes against the fins rotating 20 the cleaning element 5 within the stationary cleaning element 2 and the water saturates the bristles of the cleaning element 5 and passes onto the surface of the article being scrubbed or washed, thereby removing foreign matter from the surface of the article 25 that has been loosened by the rotation of the cleaning element 5. The bristles of the stationary cleaning element 2 confine the water

and prevents the same from being thrown by centrifugal force over too large an area. 30

While I have shown and described the preferred embodiment of my invention, it will be understood that minor changes in construction, combination, and arrangement of parts may be made without departing 35 from the spirit and scope of the invention as claimed.

Having thus described my invention what I claim is:—

A brush comprising a casing, a stationary cleaning element carried by said casing, a rotatable cleaning element carried by said casing, a nozzle carried by said casing and arranged at the inclination to the casing, fins carried by the rotatable cleaning element, a 45 handle secured to the casing and inclining toward the nozzle, a hose clamp carried by said handle and adapted to be attached to a hose for supporting the same in alignment with the nozzle and away from the casing. 50

In testimony whereof I affix my signature in presence of two witnesses.

RAYMOND L. CHEATHAM.
